UNITED STATES PATENT OFFICE.

LOUIS M. BAYRON, OF NEW YORK, N. Y.

COMBINATION TOILET SET.

Application filed April 17, 1923. Serial No. 632,712.

To all whom it may concern:

Be it known that I, LOUIS M. BAYRON, a citizen of the United States, residing at New York, in the county of New York and State 5 of New York, have invented certain new and useful Improvements in a Combination Toilet Set, of which the following is a specification.

This invention relates to improvements 10 in combination toilet sets, and has for its prime object to provide an improved combination toilet device which will be of particular value for use by travelers who wish to carry a number of toilet articles in a 15 compact form, the arrangement of the parts being such that any of the articles is readily accessible.

A further object of the invention is to provide a combination toilet set, in combination with a hair brush, whereby all the 20 toilet articles are concealed from view in a sanitary and dust-proof receptacle.

A still further object of my invention is to construct an improved combination toilet 25 set in such a manner that it can be easily and cheaply manufactured and will present a device of convenience for the traveler.

These and like objects of the invention 30 will be better understood as the description follows and as is specifically pointed out in the appended claims.

Referring to the accompanying drawing which forms a part of this specification and 35 which clearly illustrates the use and construction of my improved combination toilet set,

40 Figure 2 is a side elevation of same.

Figure 3 is a vertical section through a hair brush constructed in accordance with my invention, and

Referring to the accompanying drawing in detail, like characters will be used to designate like parts in the different views.

In the drawing, the numeral 1 indicates 50 the back of a hair brush, that is provided with the usual bristles 2.

The back of the hair brush which is provided with unusual thickness, has a slot 3 extending approximately the entire length 55 of same for receiving therein a comb 4. The open end of the slot 3 is closed and the comb retained within the slot by means of a cover 5, which engages a spring clasp 6.

Formed in the handle portion 7 of the brush and on the same side in which the bristles are embedded, are a pair of cavities 8 and 9, which are adapted to receive therein a box of rouge and face powder, as indicated by the numerals 10 and 11 respectively. The boxes 10 and 11 are concealed 60 from view and held within the cavities 8 and 9 by means of covers 12, which are hinged at one side and held in a closed position by means of a spring clamp, similar to the clamp 6.

A slot or recess 13 is formed in one side of the hair brush 1, for receiving therein lip and eyebrow sticks 14, said recess being closed and the lip and eyebrow sticks retained within said recess by means of a 70 hinged cover 15, similar to the covers 5 and 12.

Mounted on the back of the hair brush and secured thereto by any suitable means is a mirror 16, which completes my improved 80 toilet set, comprising a hair brush, comb, mirror, powder and rouge containers, and lip and eyebrow sticks.

In view of the foregoing description of my invention taken in connection with the 85 accompanying drawing, it is thought that any further explanation as to the construction, operation, and objects of my invention is unnecessary.

While I have shown and described the 90 preferred form of my invention, I realize that various minor changes may be resorted to, without departing from the spirit and scope of the invention as claimed, and therefore, I do not wish to limit myself to the exact details of construction shown, nor to the combination and arrangement of parts.

95 What I claim as new and desire to secure by Letters Patent is:

1. A toilet set of the character described, 100 comprising, a body having a rectangular recess formed longitudinally through the center thereof and a somewhat shorter recess formed on the side thereof, the front extremity of the body being shaped to form a brush and the rear extremity being shaped to form a handle, a mirror secured on the upper side of the brush retaining portion, a hinged cover adapted to close the side recess, an arcuate cover hinged to the extremity of the handle portion and adapted to cover the longitudinal recess in the body, a 105 110 pair of swinging covers secured to the lower portion of the handle and adapted to cover circular recesses formed therein, a plurality of clips to engage the covers and prevent opening thereof, and bristles formed in the lower portion of the body.

2. A toilet set of the character described comprising, a body composed of an oval shaped brush portion, and an extension portion forming a handle, the said body having a longitudinal recess formed therein adapted to receive a comb and a side recess adapted to receive lipsticks or the like and a pair of circular compartments formed in the lower extremity of the handle to receive rouge, powder and the like, a plurality of hinged covers adapted to enclose the said recesses, a plurality of clips adapted to retain the covers in the closed position when so desired, a mirror secured flush with the 20 upperside of the oval brush retaining portion, and a plurality of bristles secured in the lower portion of the brush retaining member.

In testimony whereof, I have affixed my 25 signature in the presence of two witnesses.

LOUIS M. BAYRON.
